UNITED STATES PATENT OFFICE

PHILO A. ORTON, OF CHICAGO, ILLINOIS, ASSIGNOR TO ORTON CRANE & SHOVEL CO., OF HUNTINGTON, INDIANA, A CORPORATION OF INDIANA

EXCAVATING MACHINE

Application filed November 25, 1927. Serial No. 235,495.

The invention relates to improvements in excavating machines of the type employing a swinging boom and a ditcher stick pivoted to the end thereof.

5 One object of the invention is to provide an improved construction of this character having improved means for effecting the dumping or discharging operation.

Another object of the invention is to provide a shifting lever connection with the ditcher stick, whereby the discharging operation is positively and forcibly performed.

Another object of the invention is to provide a shifting lever connection for the ditcher stick, whereby an effective leverage is exerted on the dipper stick throughout its turning movement from retracted to extreme dumping position.

Other objects will appear hereinafter.

20 In the specific embodiment of the invention illustrated in the drawings, the foregoing objects are attained by providing the ditcher stick at its top with a T-head having arms extending both inwardly and outwardly from the top of said ditcher stick. The inwardly extending arm is pivotally connected with the free or swinging end of the excavator boom and is also arranged to engage a stop thereon to limit the outward or discharging motion of the ditcher stick. A link is pivotally connected with the outer end of the outer arm of the T-head and is provided with a supporting projection arranged to rest upon the boom pivot when the ditcher stick is 25 drawn inwardly. Said link carries a sheave or pulley over which the hoisting line or cable operates. At its lower end the ditcher stick carries a rigid scoop operating to fill upon inward swinging of the ditcher stick and to discharge upon outward swinging thereof. The usual drag line or cable is 30 connected with this scoop.

The invention consists in the combinations and arrangements of parts hereinafter described and claimed.

The invention will be best understood by reference to the accompanying drawings forming a part of this specification and in 50 which,

Fig. 1 is a partial side view of an excavating machine embodying the invention;

Fig. 2 is an enlarged detail section taken substantially on line 2—2 of Fig. 1;

Fig. 3 is a side view showing the relative 55 positions of the parts when the boom is elevated and just prior to the discharging operation;

Fig. 4 is a view similar to Fig. 3 but showing the parts in an intermediate position of 60 the discharging operation, and

Fig. 5 is a similar view showing the positions of the parts at the end of the discharging operation.

The preferred form of construction, as illustrated in the drawings, comprises a suitable body or support 1 mounted, as indicated, to swing or rotate laterally on the usual caterpillar tractor 2, as indicated. The body 1 carries the usual upwardly swinging boom 3 pivoted at 4 on the body 1, said body being also provided with the usual cabin or housing 5. The construction already described is old and well known for the purpose, and constitutes no part of my present invention, except in so far as the same co-operates with other parts to be presently described. 65

A swinging ditcher stick 6 is pivotally mounted on the free or swinging end of the boom 3, said ditcher stick being provided at 70 its lower end with any usual or desired form of scoop 7 connected to be operated by a drag line or cable 8 operated from suitable hoisting mechanism indicated at 9 on the body 1. 75

The scoop 7 is the usual scoop for the purpose, filling in the usual way by inward swinging of the ditcher stick 6, and discharging by outward swinging of said ditcher stick when the boom is elevated, as indicated by the dotted lines in Fig. 1. The drag line or cable 8, and the hoisting apparatus, indicated at 9, are the usual elements for the purpose and require no further description here. 85

The ditcher stick 6 comprises a T-head 10 having arms projecting both inwardly and outwardly therefrom. Said inwardly projecting arm extends between the side channels of the boom 3, and is pivotally mounted on the pivot pin 11, which traverses the space between said side channels of said boom. 95 100

The inner end of said arm is also arranged to contact with a stop-bar 12 traversing the lower edges of the boom channels, as shown, said arm and stop being arranged to engage 5 when the ditcher stick 6 is in its extreme outermost position, as indicated in Figs. 1 and 5. The outer arm of the T-head 10 is connected, at a point substantially horizontally opposite the pivot pin 11, when the ditcher 10 stick hangs vertically, by a pivot pin 13 with a link 14 having a hoisting line sheave or pulley 15 rotatably mounted at its free end. The hoisting pulley 15 is operatively connected in the usual way with the usual hoisting line or cable 16 connected with the hoisting 15 apparatus on the body 1, in the usual way, to serve as a means for elevating the boom 3.

The link 14 is provided with additional 20 pivot holes 14' for mounting the pulley 15, whereby the link may be shortened, if desired. The link 14 carries a central supporting projection 17, adapted and arranged to rest upon and slidably engages the pivot pin 11, as indicated in Fig. 3, when the ditcher stick 6 is drawn inwardly.

In operation the scoop 7 is filled with material in the usual way by lowering the boom 3 to bring the scoop into contact with the 30 ground, as indicated in Fig. 1. The ditcher stick is then drawn inwardly by means of the drag line 8, the hoisting line 16 being simultaneously payed out. After the scoop has been filled with material by such inward 35 movement of the ditcher stick, the boom is elevated and swung laterally in the usual way to discharging position, and the drag line 8 payed out to effect discharge of the material from the scoop. When the tension on the 40 drag line is relieved, the weight of and on the boom 3 is exerted through the pivot pin 11 to cause downward and outward swinging of the boom and corresponding upward and outward swinging of the ditcher stick. During 45 the first part of this discharging movement the support 17 rests upon the pivot pin 11, the ditcher stick 6 swinging upwardly and outwardly about the pivot pin 11. However, as soon as the pivot pin 13 and the axis 50 of the pulley 15 come into alignment with the line of draft of the hoisting cable, further outward swinging of the ditcher stick causes disengagement of the support 17 from the pivot pin 11, as indicated in Fig. 4, and number 55 14 thereupon becomes a link connecting the hoisting cable 16 with the T-head 10 at the point 13, the leverage tending to swing the ditcher stick outwardly being, at the same time, shifted or transferred directly to said 60 T-head, which then acts as a simple lever.

With the construction shown and described, it is obvious that the T-head 10 and links 14 will form a compound lever acting to swing the ditcher stick outwardly into dumping 65 position and also providing for falling move-

ment of the boom through an arc corresponding to such swinging movement of the ditcher stick, when the drag line is released.

Thus, by properly proportioning the leverages, it is obvious that, under contemplated working conditions, the scoop can be dumped from any position by merely releasing the drag line, whereupon further outward swinging movement of the ditcher stick is effected by the weight of and the load on the boom applied at the pivot 11, acting to turn the T-head 10 about its pivot 13 which is now anchored by the cable 16 and link 14, the relation being such that an effective leverage will at all times be exerted on said ditcher stick from retracted to full dumping position.

When the ditcher stick reaches the limit of its outward swing, as indicated in Fig. 5, the inner end of the inner arm of the T-head 10 comes in contact with the stop 12 to limit such 85 outward swing and, if the cable 8 is payed out with sufficient speed, such stopping contact may be effected with considerable shock or jar, thus tending to loosen and discharge the material from the scoop 7.

It will be observed that at the time of discharge of the scoop 7, when the parts are in the positions indicated in Fig. 5, a powerful and effective leverage is exerted on the ditcher stick 6, tending to force the same outwardly 95 and hold it in its extreme outward position. Thus, substantially the full length of the boom and ditcher stick are always available for effecting discharge of the material from the scoop at the greatest possible distance 100 from the support 1, and also at intermediate points, if desired, and a powerful leverage exerted for swinging the loaded scoop upwardly into its discharging position. It will also be noted that the pivot pins 11 and 13 are on opposite sides of the ditcher stick 6 and are substantially directly opposite each other so that, when the ditcher stick is extended outwardly, as in Fig. 5, the pin 13 is well above, and a little outside the vertical through pin 11. This insures an effective leverage on the ditcher stick as it raises in discharging and particularly at the final discharging position.

The specific details and arrangement of parts disclosed constitutes a simple and effective one for the purpose.

While I have illustrated and described the preferred form of construction for carrying the invention into effect, this is capable of variation and modification without departing 120 from the spirit of the appended claims. I, therefore, do not wish to be limited to the precise details disclosed, but desired to avail myself of such variations and modifications as fall within the scope of the appended 125 claims.

I claim:

1. The combination with the swinging boom of an excavating machine, of a ditcher stick having a T-head at its upper end projecting 130

- laterally from each side thereof; a pivotal connection between one arm of said T-head and said boom; a hoisting cable operatively connected with the other arm of said T-head
- 5 at a point substantially horizontally opposite said first pivot when said stick hangs vertically; a scoop at the lower end of said ditcher stick; and a drag cable for operating said scoop.
- 10 2. The combination with the swinging boom of an excavating machine, of a ditcher stick having a T-head at its upper end projecting laterally from each side thereof; a pivotal connection between one arm of said T-
- 15 head and said boom; a link pivotally connected at one end with the other arm of said T-head at a point substantially horizontally opposite said first pivot when said stick hangs vertically; a sheave at the other end of said
- 20 link; a hoisting cable operating over said sheave; a scoop at the lower end of said ditcher stick; and a drag cable for operating said scoop.
3. The combination with the swinging boom of an excavating machine, of a ditcher stick having a T-head at its upper end projecting laterally from each side thereof; a pivotal connection between the inner arm of said T-head and said boom; a link pivotally
- 25 connected at one end with the outer arm of said T-head at a point substantially horizontally opposite said first pivot when said stick hangs vertically; a sheave at the other end of said link; a hoisting cable operating over
- 30 said sheave; a support on said link arranged to rest upon the pivot connection with the boom when said boom is being elevated; a scoop at the lower end of said ditcher stick; and a drag cable for operating said scoop.
- 40 4. In combination, a swinging boom bifurcated at its upper end; a pivot pin traversing the bifurcation in said boom; a ditcher stick having a T-head at its upper end projecting laterally from each side thereof, the inwardly
- 45 extending arm of said T-head being pivotally mounted on said pivot pin; a link pivotally connected at one end with the outer arm of said T-head at a point substantially horizontally opposite said first pivot when said stick
- 50 hangs vertically; a sheave at the other end of said link; a hoisting cable operating over said sheave; a supporting projection on said link intermediate its ends and arranged to rest upon said pivot pin when said boom is
- 55 being elevated; a scoop at the lower end of said ditcher stick; and a drag cable for operating said scoop.
5. In combination, a swinging boom; a ditcher stick; a pivotal connection between
- 60 said ditcher stick and boom located on the inner side of said ditcher stick; a link having a pivotal connection with said ditcher stick located on the outer side of said ditcher stick at a point substantially horizontally opposite
- 65 said first pivot when said stick hangs ver-
- 70 tically; a support on said link arranged to rest upon the pivotal connection between the ditcher stick and boom; and means for operating said boom and ditcher stick.
6. In combination, a boom; a ditcher stick; a pivotal connection between said ditcher stick and boom located on the inner side of said ditcher stick; an arm on said ditcher stick projecting from the side thereof opposite said pivotal connection; a link having
- 75 a pivotal connection with the outer end of said arm at a point substantially horizontally opposite said first pivot when said stick hangs vertically; a support on said link arranged to rest upon the pivotal connection with the boom; a hoisting cable connected with the inner end of said link; a scoop at the lower end of said ditcher stick; and a drag cable connected with said scoop.
- 80 7. In combination, a swinging boom; a ditcher stick pivoted to said boom; a scoop at the lower end of said ditcher stick arranged to fill by inward swinging of said ditcher stick and dump upon outward swinging thereof; a drag cable connected to cause inward
- 85 swinging of said ditcher stick; an arm on said ditcher stick projecting from the side thereof opposite said boom; a link pivotally connected at one end with said arm at a point substantially horizontally opposite said first
- 90 pivot when said stick hangs vertically; a support on said link resting on the boom pivot when said scoop is drawn inwardly; a sheave at the other end of said link; and a hoisting cable connecting with said sheave.
- 95 8. In combination, a swinging boom; a ditcher stick pivoted to said boom; a scoop at the lower end of said ditcher stick arranged to fill by inward swinging of said ditcher stick and dump upon outward swinging thereof; a drag cable connected to cause inward
- 100 swinging of said ditcher stick; an arm on said ditcher stick projecting from the side thereof opposite said boom; a link pivotally connected at one end with said arm at a point substantially horizontally opposite said first
- 105 pivot when said stick hangs vertically; a support on said link resting on the boom pivot when said scoop is drawn inwardly; a sheave at the other end of said link; and a hoisting cable connecting with said sheave.
- 110 9. In combination, a swinging boom having a bifurcated upper end; a pivot pin traversing said bifurcation; a ditcher stick; a T-head at the upper end of said ditcher stick, the arms of said T-head projecting inwardly and outwardly therefrom; a pivotal connection between said inwardly projecting arm and said boom pivot; a scoop at the lower end of said ditcher stick arranged to fill by inward swinging of said ditcher stick and dump upon outward swinging thereof; a drag cable connected to cause inward swinging of said
- 115
- 120
- 125
- 130

ditcher stick; a link pivotally connected at one end with said outwardly projecting arm on said ditcher stick at a point substantially horizontally opposite said first pivot when said stick hangs vertically; a support on said link resting on said boom pivot when said scoop is drawn inwardly; a sheave at the other end of said link; a hoisting cable connected with said sheave; and a stop on said boom engaging the inwardly extending arm on said ditcher stick to limit the outward swinging of the ditcher stick.

10 11. In combination, a swinging boom; a ditcher stick pivoted at its inner side to said boom; a hoisting cable operatively connected with the outer side of said ditcher stick at a point substantially horizontally opposite the pivot on the boom when said ditcher stick hangs vertically; a scoop on said ditcher stick; and means for operating said scoop.

15 12. In combination, a swinging boom; a ditcher stick provided at its upper end with inwardly and outwardly projecting arms; a pivotal connection between said inwardly projecting arm and said boom; a hoisting cable connected with said outwardly projecting arm at a point substantially horizontally opposite the pivot on the boom when said ditcher stick hangs vertical; a scoop at the 20 lower end of said ditcher stick; and means for operating said scoop.

25 13. The combination of a boom pivoted to swing vertically, a ditcher stick having a T-head at its upper end which projects laterally at both sides thereof, pivotal connection between one arm of said T-head and said boom, a link pivoted to the other arm of said T-head, a projection on said link which rests on and slidably engages the pin which pivotally connects said T-head to the boom, a 30 sheave rotatably mounted at the free end of said link and an operating and anchoring cable adjusted to said sheave, the relation being such that when the scoop is retracted, the point of pivotal attachment of the link to the 35 T-head will be in front of the pivot connecting said T-head to the boom and in dumping position of the scoop will be above said pivot whereby the weight of the boom and the load 40 sustained thereby will exert an effective leverage on the ditcher stick throughout its turning movement to dumping position.

45 14. The combination as specified in claim 12, which also comprises a stop which limits 50 turning movement of the ditcher stick outwardly.

In witness that I claim the foregoing as my invention, I affix my signature this 22d day of November, A. D. 1927.

60 PHILo A. ORTON.
